UNITED STATES PATENT OFFICE.

CURTIS G. VON ZASTROW, OF CHATHAM, NEW JERSEY, ASSIGNOR, BY MESNE ASSIGNMENTS, TO WESTERN ELECTRIC COMPANY, INCORPORATED, A CORPORATION OF NEW YORK.

SIGNALING SYSTEM.

Application filed May 12, 1925. Serial No. 29,689.

This invention relates to signaling systems and more particularly to improvements in signaling over transmission lines with high frequency alternating current within the voice range.

In toll line equipments for extending connections between exchanges where high frequency alternating current within the voice range is used for the compositions of the various signals for dialing and other control purposes, it is often desirable to suspend the transmission of signals in one direction temporarily or permanently, as the case may be, for the transmission of signals in the opposite direction over a transmission line. In a system of this sort and in particular in systems where the high frequency used for all of the signals is the same; as for example, in such systems as are described in Patent No. 1,573,991, granted to P. B. Murphy, February 28, 1926, it is of particular importance that the apparatus used for signal suspension functions with accuracy even though the fundamental frequencies employed for the signals in opposite directions are not exactly the same. For example it might happen and it is indeed, not always possible to adjust these frequencies to the desired sameness, and consequently, when signals from one end of the line are in progress of being transmitted and the signals from the other end of the line are applied for purposes of suspending the first mentioned signals, so called beats or temporary waves of a greater or smaller magnitude may be formed that may be of such nature and frequency of occurrence as to cause disturbances to be set up in the receiving apparatus that will interfere with the functioning thereof to the extent of preventing the desired suspension of signals to take place.

It is an object of this invention to provide, for systems of the above type, an improved signal suspension means so arranged that commercial variations in the common fundamental frequency used for the signals

in opposite directions will not affect the proper functioning thereof.

Another object of the invention is the provision of such a signal suspension means that functions equally well in systems where the fundamental frequencies for the signals in opposite directions are of quite different frequency.

55

To attain these and other objects there is provided in accordance with one feature of the invention, a relay arrangement whereby a signal responsive circuit at one station, by means of which the transmission of signals from this station is suspended, is made responsive to incoming signals only during the interval of no current flow which interval forms part of the transmission of signals from this station.

65

Another feature of this invention resides in the provision of a circuit arrangement whereby the said signal responsive circuit is cut off from or made unresponsive to signals outgoing from the station of which it forms a part.

70

By these arrangements, it is readily seen that it is immaterial whether or not the same fundamental frequency is employed for the signals in opposite directions as absolutely no interference between such signals can occur due to the fact that signals in opposite directions can only be transmitted and received alternately.

75

The invention has been illustrated in the accompanying drawing as applied to a toll transmission line which shows at the outgoing end means for transmitting and receiving various combinations of high frequency alternating current impulses while the incoming end is similarly equipped and also shows the circuit means arranged in accordance with this invention whereby signals outgoing from this end are suspended by signals incoming thereto.

80

Referring now to the drawing, this toll line, as illustrated, may take the place of the toll line in a system such as that fully described in the above mentioned patent

granted to P. B. Murphy. No portions of this system have been illustrated as it forms no part of this invention and in the following description only certain features of such a system will be referred to as have a direct bearing on the functioning of the invention as employed in this type of toll line. Wherever, therefore, reference is made in the following description to such a system, it is understood that for further information of possible interest, reference may be made to the text of the above mentioned patent.

Assuming then, for example, that a connection over this toll line is desired, the operations taking place in the toll line circuit will be as follows:

The immediate result of a toll operator plugging in at jack 1 will be the operation of relay 2 in an obvious manner over the sleeve circuit to ground through the two windings of this relay in series. The operation of relay 2 causes current from a 1000 cycle alternating current source interrupted at a forty cycle rate to be transmitted over the toll line to the inward end thereof. The circuit path at the outward end of the toll line for this signal is as follows: from the 1000 cycle source interrupted at the forty cycle rate through the lower and upper-inner armatures and back contacts of relay 3, the lower-inner and upper-inner armatures and front contacts of relay 2 to the talking conductors of the toll line through the upper armature and lower-inner armature and back contacts of relay 4 to the toll line towards the inward end thereof. The operation of relay 2 also closes a shunting circuit for relay 5 at its lower-outer armature and front contact to ground causing this relay 5, which is slow to release, to close an obvious energizing circuit for relay 3 which in operating opens the circuit for the signal from the 1000 cycle source interrupted at the forty cycle rate. The period of application of this signal to the line is therefore very short and governed by the slow to release characteristic of relay 5. This signal besides being transmitted out over the toll line is also transmitted through the receiving and amplifying circuit 50 which is in every detail the same as that shown in the Murphy patent. The effect of this signal is that relay 6 alternately operates and releases at the rate of forty times per second and this in turn causes the alternating current responsive relay 7 to be operated through circuits alternately charged and discharged in a manner believed to be obvious, as this relay 6 is particularly designed to respond to current impulses of this rate. The operation of relay 7 closes a shunt circuit to ground at its armature and front contact for the slow to release relay 8 which, in releasing, closes a circuit for the energization of relay 9 as

follows: battery, winding of relay 9, lower armature and back contact of relay 10, armature and back contact of relay 8 to ground. The operation of relay 9 closes a circuit for relay 10 to ground at the armature and front contact of relay 11 and when relay 8 is again operated at the cessation of the signal from the 1000 cycle source interrupted at the forty cycle rate, relay 10 will operate as the shunt circuit for relay 10 to the armature and back contact of relay 8 is opened. On the operation of relay 10 a locking circuit is closed for relays 9 and 10 from battery through the windings of these relays, the armature and front contact of relay 9 to ground at the armature and front contact of relay 11. The purpose of the operation of these two relays will become apparent as the description proceeds.

The immediate effect of the signal from the 1000 cycle source interrupted at the forty cycle rate at the inward end of the toll line will be as follows: It will be noted that this signal will pass through a receiving circuit 100 identical to the receiving set 50 and there cause the alternate operation and release of relay 101 at forty times per second. This action on the part of relay 101 results in the operation of the alternating current relay 102 which is similar to relay 7 in the receiving circuit 50, in that it responds only to alternating current impulses received at this rate. The operation of relay 102 closes a shunt circuit for the slow to release relay 103 which in releasing closes an energizing circuit for relay 104 as follows: battery, winding of relay 104, lower-outer armature and back contact of relay 111, armature and back contact of relay 103 to ground. This causes the operation of relay 104 which closes an obvious energizing circuit for lamp 106 and a locking circuit for itself through its lower armature and front contact to ground at the lower inner armature and back contact of relay 107.

The lighting of lamp 106 indicates to the inward operator that this particular toll line has been selected by the toll operator for the extension of a connection to a subscriber's line, the number of which has been given the inward operator through the usual call wire as is well known in the art. The inward operator will therefore insert plug 108 in the desired subscriber's jack and relay 107 will thereby be operated and cause the release of relay 104 and the extinguishing of lamp 106 as it will be noted that at this time the alternating current signal from the 1000 cycle source interrupted at the forty cycle rate will have been removed from the toll line and consequently the relays energized through the receiving circuit 100 released.

As is well known in the art, the connection of plug 108 to a subscriber's line will bridge

the tip and ring leads through a battery loop so that relay 109 connected through the retardation coil 110 across the tip and ring conductors of the toll line will now operate. 5 The operation of relay 109 closes an obvious energizing circuit for relay 111. The operation of relay 111 closes a circuit for relay 113 from battery through the upper winding of relay 113, upper inner armature and 10 front contact of relay 111 through the interrupter 114 to ground. Interrupter 114 is designed to interrupt this circuit at forty times per second thus causing relay 113 to operate and release at this rate. The circuit 15 for the lower winding of relay 113 through to the upper outer armature and front and back contacts of relay 111 is for the purpose of securing a more positive action of relay 113 as is well known in the art. 20 The operations of relay 113 cause signals from the 1000 cycle alternating current source to be transmitted to the toll line at forty times per second. That is, current from the 1000 cycle source repeated through 25 the repeating coil 114 and connected through the inner lower armature and front contact of relay 111 to the ring side of the line will be connected through the toll line loop to the tip side of the line through the armature 30 and front contact of relay 113 to ground at a forty cycle rate. These signals of 1000 cycle current will now be received at the outward end through the receiving circuit 35 to cause the operation of relays 6 and 7 and the release of relay 8 as hereinbefore described, and as relay 10 is now operated, the ground applied at the armature and back contact of relay 8 will be connected through the lower armature and front contact of relay 40 to the middle point of the two windings of relay 2 and thus shunt the upper high resistance winding of this relay causing an increase in the sleeve current sufficient to light the supervisory lamp at the toll operator's cord circuit as is well known 45 in the art. The lighting of this lamp indicates to the toll operator that the inward operator has extended the connection to the wanted subscriber's line and the ringing of 50 the subscriber's line may be begun.

The toll operator now applies current to the tip and ring conductors of the toll line in the usual manner to cause the operation of relay 13. The operation of relay 13 closes 55 an obvious circuit for relay 4 which, in operating, closes at its upper and lower inner armatures and front contacts a circuit to the toll line for current from 1000 cycle source which is connected to the upper and lower armatures and back contacts of relay 60 14. This signal is of short duration as relay 4 opens the energizing circuit for relay 15 which is slow to release but which in releasing closes an energizing circuit for relay 14 65 which in turn opens the circuit from the

1000 cycle source. The operation of relay 14 in opening the connection to the 1000 cycle source also closes at its upper and lower armatures and front contacts a circuit to a 1000 cycle source interrupted at a twenty cycle rate which is connected through the armatures and back contacts of relay 16.

It will be seen, therefore, that the immediate result of the operation of the ringing key at the toll operator's position will be a short signal from the 1000 cycle source followed by a prolonged signal from the 1000 cycle source interrupted at the twenty cycle rate. The purpose of the first signal is to suspend the transmission from the inward end of current from the 1000 cycle source interrupted at the forty cycle rate and the purpose of the second signal is to cause ringing current to be transmitted from the toll line to the subscriber's line. The effect of this first signal will now be described. As the relay 113 is now operating and releasing at the forty cycle rate it should be noticed that on every release of relay 113 a circuit is completed at its armature and back contact for the toll line to the receiving circuit 100 and therefore the signal from 1000 cycle source incoming over the toll line will be received at a receiving circuit 100 in the form of a signal of 1000 cycle current interrupted at a forty cycle rate. That is, this signal will be received while relay 113 is released and the signal outgoing from this end will be transmitted while the relay 113 is operated. This signal incoming to the receiving circuit 100 will therefore cause the operation of relays 101 and 102 and the release of relay 103 and as relay 111 is now operated, a circuit will be closed for relay 115 as follows: battery, winding of relay 115, lower outer armature and front contact of relay 111, armature and back contact of relay 103 to ground. The operation of relay 115 closes a circuit for relay 116 through its armature and front contact, lower outer armature and front contact of relay 107 and the make-before-break contacts of relay 117 to ground although relay 116 will not operate as long as this circuit is shunted by the ground at the relay 103. However, when the first signal from the outgoing end ceases, relay 103 will again become energized and relay 116 will operate and lock in series with relay 115 to the ground at the make-before-break contacts of relay 117. The operation of relay 116 now opens the circuit for relay 111 which, in releasing, removes the energizing circuit through the interrupter 114 for the relay 113 and these two relays 111 and 113 in releasing discontinue the application of current from the 1000 cycle source interrupted at the forty cycle rate on the toll line. When now the signal from the 1000 cycle source interrupted at the twenty cycle rate is ap-

plied a circuit is provided therefor through the armature and back contact of relay 113 to the receiving circuit 100. The receiving circuit 100 responds in the same manner as 5 before to operate relay 101 but in this case the alternating current relay 118 is operated in place of relay 102 as this relay is designed to respond only to alternating current impulses received at the rate of twenty 10 per second. The operation of relay 118 closes a shunt circuit for the energizing circuit of relay 119 which in releasing closes an obvious circuit for relay 117. The operation of relay 117 opens with its lower outer 15 armature the make-before-break contacts of the locking circuit for relays 115 and 116 which are now released. Relay 111 can not however be again energized as the circuit for relay 109 is broken at the upper and lower 20 inner armatures and back contacts of relay 117. The operation of relay 117 now applies the usual ringing current to the tip and ring of the toll line at the upper and lower inner armatures and front contacts in 25 the usual manner to ring the wanted subscriber's line.

When the toll operator ceases to ring the wanted subscriber, relays 13, 4 and 14 will be released and relay 15 reenergized and consequently the application of current from 30 the 1000 cycle source interrupted at the twenty cycle rate will be discontinued and relays 101 and 118 will be released while relay 119 will be again energized and relay 35 117 released and the ringing current disconnected from the subscriber's line. The release of relay 117 reestablishes the circuit for relay 109 and consequently relays 111 and 113 will be again operated in the manner 40 hereinbefore described to again apply current from the 1000 cycle source interrupted at the forty cycle rate to the outward end of the toll line and the effect of the reapplication of this signal will be the same as hereinbefore mentioned, namely, that the resistance 45 of the sleeve circuit will be decreased and cause the lamp in toll operator's cord circuit to be lighted to indicate to the toll operator that the wanted subscriber has not 50 yet answered.

It will be seen that in this instance the application of signals from the inward end may be temporarily suspended through the application of signals from the outward end. 55 On the other hand, in case the wanted subscriber answers during the ringing, relay 109 will not operate on the release of relay 117 and consequently relays 111 and 113 will remain in normal position and permanently 60 stop the application of current from the 1000 cycle source interrupted at the forty cycle rate. The effect of this in the outward end and in the toll operator's cord circuit will of course be that the supervisory lamp will 65 remain extinguished after the application of

ringing current ceases as an indication to the toll operator that the subscriber has answered. The connection through the toll line is now completed from one end to the other and conversation may take place. 70

When the conversation has ended and the wanted subscriber hangs up his receiver, relay 109 will again be energized causing the operation of relays 111 and 113 and the reapplication of current from the 1000 cycle 75 source interrupted at the forty cycle rate to the outward end of the trunk circuit. The effect of this at the toll operator's position will be that the supervisory lamp will again be lighted this time as a disconnect signal 80 and the toll operator will then remove her plug from jack 1 causing the release of relay 2. The release of relay 2 in turn causes the reoperation of relay 5 and the release of relay 3 and as relay 10 is in operated condition a circuit for relay 4 will be closed at 85 upper armature and front contact of relay 10 from the ground at the upper outer armature and back contact of relay 2. The operation of relay 4 closes the circuit to the line 90 from the 1000 cycle source which is connected through the armatures and back contacts of relay 14. The operation of relay 4 also causes the release of the slow to release relay 15 so that this signal of 1000 cycle current 95 will only be transmitted to the line for a short interval. It will be noted that on the release of relay 15 a circuit is closed for relay 16 that may be traced as follows: battery winding of relay 16, lower armature and 100 back contact of relay 15, upper outer armature and back contact of relay 3, upper armature and front contact of relay 10, upper and outer armature and back contact of relay 2 to ground so that on the operation of 105 relay 14, on the release of relay 15, which is slow to operate as compared with relay 16, current from the 1000 cycle source interrupted at the forty cycle rate will be supplied to the toll line through the armatures 110 and front contacts of relays 16 and 14. This signal of 1000 cycle current interrupted at the forty cycle rate will however also be very short as the operation of relay 16 opens the 115 energizing circuit for relay 11, which, being slow to release, permits relays 9 and 10 to be held up for the period during which the current from the 1000 cycle source interrupted at the forty cycle rate is to be applied to the toll line. But when relay 11 releases the 120 locking circuit for relays 9 and 10 will be opened and these two relays released and on the release of relay 10 the circuit for relays 4 and 16 is opened and the release of relay 4 closes the circuit for relay 15 which in 125 turn opens the circuit of relay 14, while the release of relay 16 again closes the energizing circuit for relay 11 and all the relays in the outward end of this toll line are therefore now returned to their normal position. 130

The effect of these short signals of 1000 cycle current followed by 1000 cycle current interrupted at the forty cycle rate at the inward end will be similar to that produced when the toll line was first taken for use, that is, the 1000 cycle current signal will cause the operation of relays 101 and 102 and release of relay 103. The release of relay 103 will then close the circuit for relay 116 and when this impulse ceases, relay 116 will operate in series with 115 as hereinbefore described. The operation of relay 116 opens the circuit for relays 111 and 113 so that the application to the outward end of the toll line of the 1000 cycle current interrupted at the forty cycle rate will be discontinued. When now the short signal of 1000 cycle current interrupted at the 40 cycle rate is applied to the inward end, relays 101 and 20 102 will again be energized and relay 103 released but as relay 111 is now released, a circuit will be closed from the contacts of relay 103 for relay 104 which provides a locking circuit for itself to the inner lower 25 armature and front contact of relay 107 and also closes the circuit for the lighting of lamp 106 which now serves as a disconnect signal for the inward operator. The inward operator noticing lamp 106 lighted removes the plug 108 from the connected line 30 and relays 107, 104, 115 and 116 respectively release, thus restoring the inward end of the toll line to normal condition.

It is readily seen that in the above described system arranged in accordance with this invention, the suspension of signals is absolutely positive and that the fundamental frequency used for signals in opposite directions need not be exactly the same as the 40 signals outgoing from the inward end will not in any way interfere with the signals incoming from the outward end, when such signals are applied to the receiving set 100 and consequently no beats will occur in the 45 signals to cause disturbances in the receiving circuit. When a signal is sent out from the inward end, relay 113 is operated and the receiving circuit 100 is disconnected from the line and when relay 113 is released there 50 is no signal transmission from the inward end while the receiving circuit 100 is then closed to the line for the reception of the signals incoming to this end. It is therefore not absolutely essential that the fundamental frequencies used for signals in 55 opposite directions are of the same frequency and any desired frequencies may be used as long as the receiving circuit 100 is tuned to the particular fundamental frequency used for the incoming signals. However, it is of considerable advantage to use the same fundamental frequency for the signals transmitted in opposite directions in systems of this type as it will reduce the 60 necessary frequency sources to one at each

exchange while in cases where different frequencies are employed, it is necessary to maintain a number of different frequency machines at each exchange.

It should be pointed out that this invention is not limited in its application to systems of the type described above but may be equally well employed in such systems where signals outgoing from either end of a line are required to be suspended. 70

What is claimed is:

1. In a signaling system, a line, means for transmitting alternating currents interrupted at certain rates over said line in one direction, means for receiving said interrupted alternating currents, a signal responsive to said last means, means associated with said receiving means for transmitting currents of the same character over said line in the other direction, and means responsive to the reception of currents by and responsive to said receiving means for interrupting the operation of said associated transmitting means during the period of the said reception. 80

2. In a signaling system, a line, means for transmitting impulses of high frequency alternating currents within the voice frequency range over said line in one direction, means for discontinuing this transmission of impulses consisting of means responsive to the reception of an impulse of the same fundamental frequency from the opposite end of the line during the transmission of no impulses of the first mentioned end of the line followed by the reception of impulses of the same fundamental frequency at a certain rate from said opposite end of the line and means for resuming the transmission of impulses from the first mentioned end of the line responsive to the discontinuing of the transmission of said last mentioned impulses. 95

3. In a signaling system, a line comprising an outward end and an inward end, a source of alternating current at said inward end for transmitting signaling current to said outward end, a source of alternating current at said outward end for transmitting signaling current to said inward end, a receiving circuit at said inward end, a relay at said inward end for alternately connecting said first source of current to said line and for connecting said receiving circuit to said line, and means controlled by said receiving circuit responsive to reception of current from said second source for disconnecting said first source of current from said line. 110

4. In a signaling system, a line comprising an outward end and an inward end, a source of alternating current at said inward end for transmitting signaling current to said outward end, a source of alternating current at said outward end for transmitting 125

signaling current to said inward end, a receiving circuit at said inward end, a relay at said inward end for connecting said first source of current to said line, a second relay for alternately rendering said connection effective and for connecting said receiving circuit to said line, and means controlled by

said receiving circuit responsive to current from said source at said outward end for restoring said relays to normal and connecting said receiving circuit to said line.

In witness whereof, I hereunto subscribe my name this 7 day of May, A. D., 1925.

CURTIS G. VON ZASTROW.
